E. H. BELDEN.
VEHICLE BODY.
APPLICATION FILED JUNE 4, 1917.

1,383,374.

Patented July 5, 1921.

UNITED STATES PATENT OFFICE.

EDWARD H. BELDEN, OF TOLEDO, OHIO, ASSIGNOR, BY MESNE ASSIGNMENTS, TO THE WILLYS-OVERLAND COMPANY, OF TOLEDO, OHIO, A CORPORATION OF OHIO.

VEHICLE-BODY.

1,383,374.

Specification of Letters Patent.

Patented July 5, 1921.

Application filed June 4, 1917. Serial No. 172,740.

To all whom it may concern:

Be it known that I, EDWARD H. BELDEN, a citizen of the United States, residing at Toledo, in the county of Lucas and State of Ohio, have invented certain new and useful Improvements in Vehicle-Bodies, of which I declare the following to be a full, clear, and exact description.

This invention relates to improvements in vehicle bodies, and particularly to vehicle bodies of the convertible type which may be converted from an open to a closed body by the complete removal of the pillars, which serve as guides for the windows, the windows being dropped into the body.

The principal object of this invention is to provide in a convertible body of this type, a complete removable pillar construction, which avoids the use of hinge connections at either top or bottom, the connections between the pillar and the top and body being effected by means of detachable connections which serve to tension the pillar longitudinally. A further object of my invention is to provide a removable pillar construction of such a nature that the pillar can be removed by a straight lateral movement thereof without any tilting, twisting or turning. Another object of my invention is to provide a removable pillar detachably connected at the ends to the top and body respectively by means of yielding detachable connections which exert a longitudinal stress upon the pillar.

Further objects, and objects relating to economies of manufacture and details of construction will definitely appear from the detailed description to follow. I accomplish the objects of my invention by the devices and means described in the following specification. The invention is clearly defined and pointed out in the appended claims.

A structure constituting a preferred embodiment of my invention is illustrated in the accompanying drawing, forming a part of this specification, in which

Figure I is a fragmentary view in side elevation of a motor vehicle embodying my invention. Fig. II is an enlarged, fragmentary, sectional view, taken on the line II-II of Fig. I. Fig. III is an enlarged, fragmentary view in side elevation, showing the connection between the upper end of the removable pillar and the top. Fig. IV is a fragmentary, sectional view taken on the line

IV-IV of Fig. II. Fig. V is a view similar to Fig. IV showing the locking means released to permit of the removal of the pillar. Fig. VI is a detail, perspective view of one of the keepers carried by the top and body. Fig. VII is a detail perspective view of the upper end of the face plate covering the locking device. Fig. VIII is an enlarged, fragmentary, detail, sectional view taken on the line VIII-VIII of Fig. III. Fig. IX is an enlarged sectional view taken on the line IX-IX of Fig. III.

Similar reference numerals refer to similar parts throughout the several views, and the sectional views are taken looking in the direction of the little arrows at the ends of the section lines.

Considering the numbered parts of the drawings, I have shown my invention embodied in a motor vehicle comprising a body 75 10, a permanent top 13, and removable pillars 14, disposed between said top and body, and serving as guides for the windows 15. At the top and bottom of the removable pillars, there are provided recesses 16, in which 80 the locking devices are disposed. Since these locking devices are the same at both top and bottom and operate in exactly the same way, I will describe but one of them.

The face plate 17 is secured to the pillar 14 85 by the screws 18, and covers the recess 16 in the pillar. The upper end 19 of said face plate is bent rearwardly and mortised into the upper end of the pillar. The latch 21 is disposed in the recess 16, and is provided 90 with an upwardly bent tongue 20, which is riveted to the face plate 17, and with upwardly extending parallel spring locking arms 23, which toward their upper ends are bent toward each other and extend through 95 an opening 25, in the portion 19 of the face plate. These arms are provided with the outwardly and upwardly directed beveled fingers 24 as clearly shown in Figs. IV and V. Yoke 26 is carried by the face plate 17 100 and the spindle 27 carrying the locking cam 28 is pivotally mounted in the face plate 17 and the yoke 26, with said locking cam 28 disposed between the spring arms 23 of the latch. The outer end of the spindle 27 is 105 provided with a polygonal head 29 to receive a wrench or suitable device for turning the spindle. A keeper is secured to the top 13 in position to be engaged by the locking device and comprises an angle plate having a verti-

cal portion 30 and a horizontal portion 33. An opening 34 is provided in the horizontal portion, corresponding to the opening 25 in the portion 19 of the face plate 17, and there is also provided a narrow mouth 35 for said opening 34. A slot 36 is provided in the vertical portion 30 of the keeper, said slot being somewhat wider than the opening 34, and connecting with the mouth 35, so that said opening 34, the mouth 35 and the slot 36 together make one complete opening through which the fingers 24 of the latch may pass when inserting the removable pillar in place.

15 From the description of the parts given above, the operation of my device should be very readily understood. In Figs. I, II and IV, I have shown the pillar locked in position with respect to the vehicle body. It will be seen that the cams 28 are rotated so as to separate the arms 23 and force the locking fingers 24 into engagement with the edges of the openings 34 of the keepers mounted in the top and body respectively. 20 25 The locking fingers 24 are beveled upwardly and outwardly so that as they engage the edges of the opening 34, when they are separated by means of the cam 28, they will tend to draw the top 13 toward the upper end 30 of the pillar 14, and, similarly, the latch 21 on the lower end of the pillar will tend to draw the pillar toward the body 10, so that, when the removable pillar is in place, and the locking devices are locked, the pillar 35 will be drawn tightly against the body 10 and the top 13 will be drawn tightly against the upper end of the pillar 14, so that the pillar is rigidly clamped in place between the top and the body. When the cam 28 40 has been rotated to separate the locking arms 23, the fingers 24 are moved laterally so that the edges thereof engage the rear face of the vertical portion 30 of the keeper to prevent lateral movement of the pillar 45 in one direction, while the opposite edges of the arm 23 engage the rear wall of the opening 34 (see Figs. II and IX) to prevent lateral movement in the opposite direction. It will be therefore evident that when the locking arms 23 are separated by the cam, the pillar is rigidly held in place, being tensioned longitudinally through the engagement of the fingers 24 with the edges of the opening 34, and being held against lateral 50 movement in both directions by the engagement of the edges of the fingers 24 with the rear face of the vertical portion 30 of the keeper and rear wall of opening 34.

In order to convert the vehicle from a closed to an open one, the windows 15 are dropped into their pockets and the cams 28 are rotated so as to allow the spring locking arms 23 to approach each other as shown in Fig. V. When said locking arms 23 have come to this position, the fingers 24 are suf-

ficiently close together that they will pass through the slot 36 in the keeper. The removable pillars can then be removed by a single lateral movement, the fingers 24 of the locking devices passing out through the slots 36. It will be seen that the pillars can be very easily released or locked in position and that the construction of the locking devices is very simple and of such a nature that it will not interfere with the finish on the inside of the vehicle, the locking devices being adapted to be concealed beneath the upholstery. It is further apparent that this removable pillar construction is such that the pillar is tensioned in place and held firmly against lateral movement or twisting or turning so as to clamp the pillar rigidly in place and prevent any rattle due to the vibration of the car.

I have found that this specific embodiment of my invention is very desirable from many standpoints, but I am also aware that it may be varied considerably without departing from the spirit of my invention, and therefore, I desire to claim my invention broadly and specifically, as indicated by the appended claims.

Having thus described my invention, what I claim as new and desire to secure by Letters Patent is:

1. In a vehicle body provided with a body portion and a top portion, the combination therewith of a demountable pillar detachable from the body and top portions by a bodily lateral movement relative thereto without tilting movement of the pillar, and means to secure said pillar in tensioned position between said body and top portions, comprising an element of a separable fastener secured to said body and top portions, respectively, a cooperating element secured to either end of said pillar, and an operating member for forcing said cooperating elements into engagement with the elements on the body and top portions, said cooperating elements being constructed and arranged to automatically move out of such engagement when released by said operating member.

2. In a vehicle body provided with a body portion and a top portion, the combination therewith of a demountable pillar, and means for detachably securing one end of said pillar to one of said portions, comprising a plate secured to the inner face of said pillar, locking arms secured to said plate and located in a recess in said pillar, said arms being movable toward and away from each other and extending beyond the end of said pillar, a member rotatably mounted in said plate and provided with a cam disposed between said arms and adapted to move the same apart, and a keeper secured to said portion and provided with a slot to permit the passage of the projecting

- ends of said arms, said ends being insertible in said slot by a lateral movement of said pillar and locked to said keeper when said arms are moved apart by said cam.
- 5 3. In a vehicle body provided with a body portion and a top portion, the combination therewith of a demountable pillar, and means for detachably securing one end of said pillar to one of said portions, comprising a keeper secured to said portion, a locking and tensioning device carried by the end of said pillar, said device comprising a pair of arms provided at their free ends with upwardly and outwardly inclined fingers engageable with said keeper to draw said portion and the end of said pillar into close-fitting engagement, and means for separating the arms of said fork to cause said inclined fingers to engage said keeper.
- 10 4. In a vehicle body provided with a body portion and a top portion, the combination therewith of a demountable pillar, and means for detachably securing one end of said pillar to one of said portions, comprising a keeper secured to said portion and provided with a slot, and a U-shaped member secured to said pillar and having out-turned ends insertible in said slot by a lateral movement of said pillar, and means for forcing said out-turned ends away from each other to lock said member and keeper together.
- 15 5. In a vehicle body provided with a body portion and a top portion, the combination therewith of a demountable pillar, and means for detachably securing one end of said pillar to one of said portions, comprising a keeper secured to one of said portions, comprising a member secured to the other of said parts and insertible in said opening by a lateral movement of said pillar in one plane, said member when located in said opening being movable laterally in a different plane to engage said keeper to bind and lock said parts together, and means for moving said member laterally.
- 20 6. In a vehicle body provided with a body portion and a top portion, the combination therewith of a demountable pillar, and means for detachably securing one end of said pillar to one of said portions, comprising a keeper secured to one of said parts and provided with an opening, a member secured to the other of said parts and having an inclined end portion, said end portion being insertible in said opening by a lateral movement of said pillar in one plane and when located in said opening being movable laterally in a different plane to engage said keeper to draw said pillar into tensioned engagement with said body or top portion, and means for moving said member laterally.

In testimony whereof I affix my signature.
EDWARD H. BELDEN.
